UNITED STATES PATENT OFFICE.

ARTHUR W. WADSWORTH, OF FORT THOMAS, KENTUCKY, ASSIGNOR TO THE WADSWORTH WATCH CASE COMPANY, OF DAYTON, KENTUCKY, A CORPORATION OF KENTUCKY.

ADJUSTER FOR METAL BANDS.

Application filed June 15, 1927. Serial No. 198,982.

This invention relates to metal bands worn with wrist watches, and has for its primary object the provision of an adjusting means whereby a metal band of a given width may 5 be used with watch cases of varying widths.

Another object of this invention is that the adjusting means also acts as a filler between the edges of the metal band and the protruding lugs of the watch case, thereby 10 giving a more pleasing appearance in the jointure between the metal band and the watch case.

Still further objects of this invention are to provide an adjuster for metal bands 15 which will be simple, efficient, durable and economical to manufacture.

Other objects and advantages will be in part indicated in the description and in part rendered apparent therefrom in connection 20 with the drawing.

This invention consists in the provision of a pair of tubular adjusting members each having a plurality of slotted recesses in one end thereof of different depths whereby 25 metal bands of varying widths may be neatly and snugly inserted and pivotally attached between the pin bar attaching lugs of a wrist watch.

To enable others skilled in the art to fully 30 apprehend the underlying features hereof that they may embody the same in the various ways contemplated by this invention, drawings depicting a preferred typical construction have been annexed as a part of this 35 disclosure, in which:

Fig. 1 is a view in perspective showing a wrist watch case having my invention installed on one end thereof;

Fig. 2 is an enlarged isometric view of one 40 of the adjusting sleeves partly broken away and shown in vertical section;

Fig. 3 is a plan view of a watch case having pin bar attaching lugs thereon and showing the inner ends of the metal bands provided with the adjusting sleeves which are positioned between said lugs;

Fig. 4 is a vertical cross section of one of the adjusting sleeves, pin bars and metal bands taken on line 4—4 of Fig. 3;

Fig. 5 is an isometric view of the looped end of one of the metal bands, part of the band being broken away;

Fig. 6 is an isometric view of one of the pin bars;

Fig. 7 is an enlarged view showing two

of the pin holding lugs, two of the adjusting sleeves, one of the pin bars and the looped end of one of the metal bands, the parts shown in horizontal section taken on line 7—7 of Fig. 8; and

Fig. 8 is a side elevation of the parts shown in Fig. 7.

In the embodiment of my invention as illustrated and which shows a preferred construction, I provide a watch case 1 of any suitable size or shape but for illustration purposes I have chosen a rectangular shape.

Usual pin bar attaching lugs 2 are mounted upon the ends 3 and 4, respectively, of said watch case 1 and are provided 70 with transverse holes 5 which detachably receive pins 6 of the usual pin bar 7.

The parts thus far described are of the usual and well-known construction.

It has been the practice in the past to supply leather straps provided with looped ends for receiving the pin bars 7 and in this way attaching said leather straps to the pin bar attaching lugs 2. Recently, however, there has been a demand created for metal bands to replace the said leather straps. This being a fact, wrist watch cases of different sizes and shapes have varying widths between the pin bar attaching lugs 2.

To insure a snug fit between the metal bands 8 and the pin bar attaching lugs 2, I have invented adjusting and spacing sleeves 9. Said adjusting sleeves 9 are each provided on their outer ends with inturned flange 10, as clearly shown in Figs. 2 and 7, 90 to form a neat and close fit with the attaching lugs and pin bar and on their inner ends with a plurality of slotted recesses 11 of different depths to permit a metal band of a given width to be attached to watch cases 95 of varying widths. The inner ends of metal bands 8 are bent upon themselves, forming loops 12 (see Figs. 4 and 5) which loops are for the purpose of receiving pin bars 7. It will also be noticed that looped ends 12 of metal bands 8 are slightly cut away at 13, thereby reducing the width of said looped ends relative to said bands, which cut away portions allow said adjusting sleeves 9 to more perfectly fit over said looped ends.

To assemble one of the metal bands 8 to the watch case 1, the first step is to insert pin bar 7 within loop 12 of said band 8. Then place one of the adjusting sleeves 9 over one end of loop 12 of said band 8, so 110

that one of the slotted recesses 11 fits over the edge 15 of said band. Then place another adjusting sleeve 9 over the opposite end of said loop 12 so that one of the slotted recesses 11 fits over edge 16 of said band, whereupon the band may be securely attached to the pin bar attaching lugs 2 by depressing pins 6 until the flanges 10 of said adjusting sleeves 9 fit between said lugs, 10 whereupon said pins 6 are forced outwardly into holes 5 of said lugs 2 by coil spring 14 within said pin bar 7, as is clearly shown in Fig. 7. As the width between the lugs 2 of watch case 1 varies, a band 8 of a given 15 width may be snugly attached therebetween by the adjustment of sleeves 9, as for example, should the metal bands 8 be of a narrower width than the distance between the lugs 2 the adjusting sleeves 9 may be so 20 placed upon loop 12 of said band 8 that the smallest slotted recess 11 may be inserted over the edges 15 and 16 of said band, thereby giving a snug fit between said band 8 and pin bar attaching lugs 2.

25 It will be understood that certain changes and modifications of the invention can be made without departing from the scope or spirit thereof as defined in the claims.

30 What I claim as new and desire to secure by Letters Patent is:

1. In combination with a watch case having lugs and a pin bar adapted to engage said lugs, a metal band having a looped end and adapted to receive said pin bar mounted 35 in said lugs and a pair of sleeves each having one end slotted to engage the respective

edges of said metal band to cause a snug fit between the band and the lugs, for the purposes specified.

2. In the combination as specified in 40 claim 1, wherein one end of each sleeve is provided with a plurality of slots.

3. In the combination as specified in claim 1, wherein one end of each sleeve is provided with a plurality of slots of varying 45 depths.

4. In combination with a watch case having lugs and a pin bar adapted to engage said lugs, a metal band having a looped end shorter than the width of said band adapted 50 to receive said pin bar mounted in said lugs, and a pair of sleeves each having one end slotted to engage the respective edges of said metal band to cause a snug fit between the band and lugs, for the purposes specified. 55

5. In the combination as specified in claim 1, wherein one end of each sleeve is inturned, for the purposes set forth.

6. In combination with a watch case having lugs and a pin bar adapted to engage said lugs, a metal band having a looped end adapted to receive said pin bar mounted in said lugs, and a pair of slotted sleeves mounted on said pin bar and engaging said metal band, one of which sleeves is provided 60 with a plurality of slots of varying depths to engage the edge of said metal band whereby a band of a given width may be attached to watches having lugs spaced apart to different widths. 65

ARTHUR W. WADSWORTH.
